UNITED STATES PATENT OFFICE

2,508,294

WATER SEAL FOR REFRIGERATOR CARS

Richard E. Powers, East Rochester, N. Y.

Application June 7, 1947, Serial No. 753,304

1 Claim. (Cl. 182—8)

1

The invention relates to a water seal and trap for a railway refrigerator car drain pipe. Such pipes are used to allow melted ice to escape and for the removal of debris from the interior of the car. Water in a bowl forming part of the seal trap overlaps the end of the drain pipe sufficiently to form a water seal to prevent refrigerated air escaping from the interior of the car to the outside thereof and at the same time preventing the entrance of hot air from the outside to the interior of the car. Just the opposite is true when the interior of the car is being heated.

Such bowls are generally swingable to allow the water to escape from the bowl and thus break the seal and allow water and debris to readily escape from the interior of the car. Such bowls must be swingable far enough away from the drain pipe to allow a stick to be used to clean out the drain pipe if necessary.

An object of the invention is to provide a resiliently hinged bowl assembly so that if the bowl is accidentally or inadvertently left in open position the bowl will automatically move to closed position when free to do so. If the bowl is left in open position, of course, there can be no seal and loss of refrigeration would result.

Further objects of the invention are to provide a structure of water seal and trap of few parts thereby providing light weight, simplicity of design and assembly, with no working parts exposed to the corrosive action of melting of the refrigerant or brine.

In the drawings:

Figure 1 shows a side elevation of my resiliently hinged bowl assembly.

Figure 2 is a bottom view of the assembly.

Figure 3 is a side elevation of the assembly.

Figure 4 is a section on line 4—4 of Figure 2.

Figure 5 is a section on line 5—5 of Figure 2.

Figures 6 and 7 show the pipe part of the bowl hinge structure.

Figures 8 and 9 show one of the fillers of the hinge structure.

Figures 10 and 11 show the spring before assembly with the base member and bowl.

In the form of the invention illustrated my resiliently hinged bowl assembly comprises a base member 2 adapted to be secured to the car 3 by any convenient means, such as the bolts 4, and is provided with an aperture 5 through which the drain pipe 6 extends. The bowl 7 is positioned below the drain pipe 6 and the pipe projects thereinto sufficiently so that water (10) in the bowl forms a seal between the interior of the car and the outside atmosphere. See Figure 1. 55

2

The base member 2 is provided with spaced sockets 12. A pipe 13 is fixed to the bowl by being welded thereto, as shown at 14 and 15. The ends of the pipe pivotally engage the sockets 12 and 12 so that the bowl 7 is hingedly or swingably supported from the base member 2.

A flat torsional spring 18 is positioned within the pipe 13 which has its central portion fixed to said pipe against torsional movement by means of the little semi-circular fillers 19 welded to the interior of the pipe and spaced apart to provide an opening for the flat spring. The end portions of the spring are fixed to the sockets 12 against torsional movement respectively by means of the little semi-circular fillers 20 secured to the sockets 12 and spaced apart to provide slots for the ends of the spring.

By this arrangement when the bowl 7 is swung to open position, that is away from the base member 2, torsional stresses are set up on the spring 18 (see Figure 2) tending to return the bowl to normal closed position, that is, toward the base member.

In assembling the bowl 7 with the base member 2 I preferably put an initial torque in the spring 18 to bias the bowl tightly against the base member. This is accomplished by adjustment of the fillers 19 and 20 before they are welded in place.

The bowl may be provided with a spout 21 and handle 22 if desired.

The accompanying drawings illustrate the preferred form of the invention, though it is to be understood that the invention is not limited to the exact details of construction shown and described, as it is obvious that various modifications thereof, within the scope of the claim, will occur to persons skilled in the art.

I claim:

40 A resiliently hinged bowl assembly for a water seal for a refrigerator car drain pipe, said assembly comprising a base member adapted to be fixed to a car adjacent said drain pipe, and having an aperture therein for the reception of said drain pipe, axially aligned spaced sockets, fixed to said base member and provided with diametrical slots, a bowl adapted to overlap the end of the drain pipe and form a water seal therewith, a pipe fixed intermediate its ends to said bowl and pivotally engaging said sockets to form a hinge between the bowl and said base member, and a flat pre-loaded torsional spring positioned within said pipe having the central portion thereof fixed to said pipe against torsional movement and having the end portions thereof fixed

in the slots of said sockets against torsional movement, whereby when the bowl is swung away from the base member torsional stresses are set up in said spring tending to return the bowl toward said base member when free to do so.

RICHARD E. POWERS.
